UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,409,157.

Specification of Letters Patent. Patented Mar. 14, 1922.

Application filed January 20, 1920. Serial No. 352,690.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt Structures; and I do hereby declare the following to be a full, clear, and exact description of the invention, such as will enable others skilled in the art to which it appertains to make and use the same.

This invention relates to improvements in staybolt structures for boilers,—one object of the invention being to provide a structure in which the bearing member shall be universally adjustable to insure accurate alignment of the staybolt with its points of connection with the respective boiler sheets and then be permanently united to the outer boiler sheet by welding, and to so construct said bearing member that it shall be capable of being mounted in the boiler sheet so that its outer end shall be flush with the outer face of the outer boiler sheet or so that it may project outwardly beyond the same and to provide such a bearing member with a removable closure which shall be located therein.

With this and other objects in view, the invention consists in certain novel features of construction and combinations of parts as hereinafter set forth and pointed out in the claims.

In the accompanying drawings,—Figure 1 is a sectional view, partly in elevation, showing an embodiment of my invention; Figures 2 and 3 are views showing different ways in which the bearing member may be connected with the outer boiler sheet; Figures 4 to 13 are views showing modifications.

1 represents an outer boiler sheet and 2 the inner sheet of a boiler.

In the embodiment of my invention shown in Figure 1, the outer boiler sheet is made with an opening 3, a portion of the wall of which is rounded as at 4, and the outer portion of said wall is made flaring as at 5.

A bearing member 6, approximately hemispherical in form has a mounting in said

opening, the rounded exterior face of said bearing member having a universally movable or adjustable mounting on the rounded seat afforded by the rounded portion 4 of the wall of the opening in the boiler sheet. The 55 bearing member 6 is made with an opening 7 at its inner end for the accommodation of a staybolt 8 and said member 6 is made interiorly near its inner end with a rounded seat 9 for the rounded head 8^a of the staybolt, the inner end of the bolt being secured to the inner boiler sheet in any suitable manner.

The bearing member 6 is hollow and is threaded interiorly for the reception of a 65 threaded plug or closure 10 and a gasket 11 may be interposed between the inner end of the latter and a shoulder 12 in said bearing member. The plug or closure 10 is formed to provide a clearance space 10^a and it may be 70 provided with an angular portion 10^b to receive a wrench.

It will be observed that the outer end of the bearing member 6 and the angular portion 10^b of the plug or closure are substantially flush with the outer face of the boiler sheet 1. The outer end of the bearing member 6 is beveled, as at 13, and this beveled face forms, with the flaring portion 5 of the wall of the opening in the boiler sheet, a 80 groove in which a weld 14 is located,—said weld fixedly uniting the bearing member to the boiler sheet.

By mounting the bearing member so that it may be universally movable relatively to the boiler sheet, it may be adjusted in a manner to insure accurate alignment of the staybolt relatively to its points of connection with the respective boiler sheets and after such adjustment shall have been effected, the bearing member will be welded to the outer boiler sheet, as previously explained.

In Figure 2 I have shown the universally adjustable bearing member mounted on the boiler sheet 1 so that it will project outwardly beyond the outer face of the sheet. In this instance a portion of the opening may be rounded as at 15, to conform to the curvature of lower or inner exterior face of the bearing member and on which the latter is 100

seated and the bearing member is united to the boiler sheet by a weld 14^a. The inner portion of the wall of the opening in the boiler sheet may be approximately cylindrical, as shown at 16.

The inner or lower end of the bearing member may be mounted on the boiler sheet as shown in Figure 3. In this instance, the major portion of the opening 17 in the boiler sheet may be made tapering and a narrow annular seat 18 formed adjacent to the outer or upper end of the opening to receive the bearing member and on which the latter is universally adjustable,—the bearing member being welded to the boiler sheet, as at 14^b.

Instead of providing a closure having an angular, wrench-engaging enlargement located within the bearing member, as shown in Figures 1, 2 and 3, the closure may be made as shown at 19, Figure 5, this closure being made with an angular wrench-receiving socket 20 and the peripheral threaded portion extending to the outer end of the bearing member.

In the embodiment of the invention shown in Figures 5 and 6, 1^a represents an outer boiler sheet and 2^a the inner sheet of a boiler. The inner end of a staybolt 3^a is secured in any suitable manner to the inner boiler sheet and said staybolt is provided with a head 4^a which is connected with the outer boiler sheet by a mounting hereinafter described.

In Figure 5, the outer boiler sheet is shown provided with an opening, a portion of the wall of which may be beveled at 5^a but the major portion of the wall of which is rounded transversely of the sheet to provide a rounded seat 6^a for the accommodation of the rounded exterior portion 7^a of a bearing member 8^a, the latter being formed with an opening at its inner end for the accommodation of the staybolt and with an interior seat 9^a for the rounded head of the staybolt. The bearing member 8^a is approximately hemi-spherical in shape and at its outer end is provided with a beveled flange 10^a which lies within the opening in the boiler sheet and forms, with the beveled portion 5^a of said wall, a groove which is occupied by a weld 11^a, said weld serving to fixedly unite the bearing member to the boiler sheet after said bearing member shall have been properly adjusted.

The hemi-spherical bearing member 8^a is threaded interiorly and receives a threaded plug or closure 12^a, the latter being made hollow to provide a clearance space 13^a for the bolt head, and with an angular portion 14^a to receive a wrench. A gasket 15^a may be located between the inner end of the plug or closure 12^a and a shoulder 16^a formed within said bearing member.

It will be observed that in Figure 5, the outer end of the structure is substantially

flush with the outer face of the outer boiler sheet.

When the structure is mounted as shown in Figure 6, a considerable portion of the same will project beyond the outer face of the outer boiler sheet,—the opening in the boiler sheet being so formed as to provide a comparatively shallow rounded seat 17^a on which the inner end of the rounded portion of the bearing member is mounted. From the inner end of the rounded seat 17^a, to the inner face of the boiler sheet, the opening in the sheet may be straight and have a diameter appreciably greater than that of the staybolt, as indicated at 18^a.

That portion of the bearing member which projects outwardly beyond the boiler sheet, is provided with circumferential recess 19^a and the upper end of this recess is counter-bored to form a circular groove 20^a. Surrounding the bearing member and located in said recess and groove is a ring or gasket 21^a of material to which a welding alloy will not cohere,—such, for example, as mineral wool or clay. A weld α surrounds the bearing member and the ring or gasket 21^a, said weld overlying the portion of the bearing member in which the groove 20^a is formed and extending to the boiler sheet. The bearing member is thus fixedly welded to the boiler sheet, but the cohesive union of the welding alloy with the metal of the bearing member is of restricted area, so that said bearing member may be more readily cut away from the weld should it become necessary to remove said bearing member.

When the bearing member is employed as a "flush" mounting, as shown in Figure 5, the ring or gasket may serve as a packing, and should it become necessary to remove the structure, this may be accomplished by cutting off the flange 10^a.

In the embodiment of the invention shown in Figure 7, 1^b represents an outer boiler sheet and 2^b the inner sheet of the boiler. The outer boiler sheet is provided with an opening, a portion of the wall of which is rounded to provide a seat 3^b for a bearing member 4^b.

The bearing member 4^b is made approximately hemispherical and its outer rounded face 5^b conforms to the curvature of the seat 3^b in the boiler sheet. The inner end of the bearing member 4^b is open for the accommodation of a staybolt 6^b and in proximity to said open end, the bearing member is provided interiorly with a rounded seat 7^b for the rounded head 8^b of the staybolt. The outer end portion of the bearing member 4^b is threaded interiorly as at 9^b to receive a plug closure 10^b, between the inner end of which and a shoulder 11^b in the bearing member, a gasket 12^b may be interposed. The closure 10^b is provided with an annular flange or head 13^b which overlies the outer

end of the wall of the bearing member and the periphery of said flange or head 13^b may be rounded to the same curvature as that of the external curved or rounded face 5^b 5 of the bearing member. The flange or head 13^b forms, with a flaring portion 14^a of the wall of the opening in the boiler sheet, a groove in which a weld 15^b is located to unite the closure with the boiler sheet and 10 the metal of this weld may extend to the upper edge of the bearing member.

Instead of mounting the device so that the outer end of the closure will be flush with the outer face of the boiler sheet, the bearing member may be mounted on a curved seat 16^b in the boiler sheet as shown in Figure 8 and a weld 17^b surrounding said bearing member uniting the same to the boiler sheet. If desired a shallow rounded 20 seat 18^b may be formed at the outer end of the opening in the boiler sheet to receive the inner end portion of the rounded exterior of the bearing member, as shown in Figure 9, and a weld 19^b unites the bearing member 25 with the boiler sheet. It will be observed that in Figures 7, 8 and 9, the closure is provided with an angular portion 20^b which lies within the annular flange or head 13^b and is intended to receive a wrench.

30 In the embodiment of the invention shown in Figure 10, a closure 21^b is employed which is threaded into the bearing member and is provided with a comparatively thin peripheral flange 22^b which rests upon the 35 end of the wall of the bearing member and is united to a portion of the wall of the opening in the boiler sheet by means of a weld 23^b, said weld also serving to secure the bearing member to the boiler sheet. The 40 closure 21^b may be provided with ribs 24^b to receive a wrench and the outer edges of these ribs may be disposed flush with the outer face of the boiler sheet. In the construction shown in Figure 11, the closure 25^b 45 is similar to the closure 21^b, shown in Figure 10, except that it is not threaded to the bearing member but its flange 22^b is welded to the boiler sheet as indicated at 26^b.

It will be observed that in all of the several 50 Figures 7 to 11 of the drawing, the internal configuration of the closures is such as to provide clearance space 27^b for the head of the bolt and it will also be observed that the head of the bolt may be ovoid in shape. 55 In the embodiment of the invention shown in Figures 12 to 15, 1^c represents an outer boiler sheet and 2^c the inner sheet of a boiler. A staybolt 3^c is secured at its inner end, in any suitable manner, to the inner 60 boiler sheet 2^c and the outer end of said staybolt is provided with an enlargement forming a head 4^c having a tapering exterior face, and this head is connected with the outer boiler sheet by means of devices hereinafter described.

The outer boiler sheet 1^c is provided with an opening, a portion of the wall of which is rounded to provide a seat 5^c for the rounded outer portion 6^c of a bearing member 7^c. This bearing member 7^c is provided with 70 a rounded seat 8^c for the rounded external surface of a bearing ring 9^c and this bearing ring is made interiorly with a conical or tapering wall 10^c which conforms to the shape of the tapering enlarged or headed 75 end 4^c of the staybolt and on which said enlarged or tapering end bears. With the use of the bearing ring 9^c inserted between the enlarged or tapering end of the staybolt and the interior seat 8^c of the bearing 80 member, the staybolt will be permitted to have the necessary "swing" incident to flexible staybolt structures and the necessity for providing the staybolt with a spherical or rounded head is obviated.

85 The bearing member 7^c is provided interiorly with a threaded portion 11^c to receive the threaded peripheral portion of a plug closure 12^c. A gasket 13^c may be interposed between the closure 12^c and a shoulder 14^c 90 in the bearing member and said closure may also be provided with an annular flange or rib 15^c depending below said shoulder 14^c. To facilitate manipulation of the closure, the same may be provided with an angular 95 portion 15^c to receive a wrench.

The bearing member 7^c may be beveled at or near its outer end as at 16^c and this beveled portion forms, with a beveled portion 17^c of the wall of the opening in the boiler 100 sheet, a groove in which a well 18^c is located to fixedly unite the bearing member to the boiler sheet. It will be observed that prior to the welding the bearing member may be adjusted to insure proper alignment of the 105 staybolt with its points of connection with the respective boiler sheets.

In Figure 13 I have shown the bearing member mounted in an opening in the boiler sheet in such manner as to project beyond 110 the latter and in this case the bearing member is united to the boiler sheet by weld 19^c.

Having fully described my invention what I claim as new and desire to secure by Letters-Patent, is:—

115

1. In a staybolt structure, the combination with a boiler sheet having an opening, of an approximately hemispherical bearing member having an initially universally movable mounting coincident with the opening 120 in the boiler sheet, a staybolt having a head mounted in said bearing member, a removable member providing a closure for the bearing member, and a weld uniting said bearing member to the boiler sheet.

125

2. In a staybolt structure, the combination with a boiler sheet having an opening, a portion of the wall of said opening being rounded, forming a seat, of a bearing member approximately hemi-spherical in outline 130

and being initially universally adjustable on the seat in the boiler sheet, with its outer end approximately flush with the outer face of the boiler sheet, said bearing member having a beveled face at its outer end forming with a portion of the wall of the opening in the boiler sheet, a groove, a weld occupying

said groove and uniting the bearing member to the boiler sheet, a closure for said bearing member, and a staybolt having a head mounted in said bearing member.

In testimony whereof, I have signed this specification.

ETHAN I. DODDS.
